UNITED STATES PATENT OFFICE.

DANIEL H. CROSS, OF SHAFTSBURY, VERMONT.

APPARATUS FOR GUMMING, CUTTING, AND MOUNTING PHOTOGRAPHIC PRINTS.

Specification forming part of Letters Patent No. 43,184, dated June 21, 1864.

To all whom it may concern:

Be it known that I, DANIEL H. CROSS, of the town of Shaftsbury, in the county of Bennington, in the State of Vermont, have invented a new and useful Machine for Gummimg, Cutting, Mounting, and Pressing Photographic Prints on Cards; and I do hereby declare that the following is a full, clear, and exact description of the same, reference being had to the accompanying drawings, making a part of this specification, in which—

Figure 1 shows a side elevation, the mounting apparatus being compressed in red lines. Fig. 2 is an end view of the machine. Figs. 3 3' are adjustable cutting-blades detached. Fig. 4 shows a plan or top view of the apparatus. Figs. 5 5' show a view of an oval cutter and a section. Fig. 6 is a detached view of the shearing-cutters. Fig. 7 shows the spring clamp detached. Fig. 8 shows a detached view of the cover of the card-receiver and the spring-follower. Fig. 9 shows a block, a portion of which is covered with canton-flannel or other soft fibrous substance for spreading the mucilage on the back of the prints in the process of gumming.

The object of my invention is to facilitate the mounting of photographic prints on the cards without having to handle each separately, which is accomplished more speedily and in a much neater manner.

My invention consists in the construction, arrangement, and combination of certain mechanical movements operating automatically as hereinafter described.

To enable others skilled in the art to make and use my invention, I will describe it in detail, referring to the drawings, and to the letters of reference marked thereon.

I make a frame or base, A, of hard wood or of metal, into which is fitted the die stand or punch B, which may be square, oval, or of any other desired shape. The die-stand B is placed and firmly secured in the center of the base A, and is elevated above the base sufficient to act as a punch to compress the print on the card through the cutting apparatus C, hereinafter described. The die stand or punch B being stationary, it being made of or faced with a plate of tempered steel, b, the upper surface being perfectly flat and the corners or edges sharp, it forms the lower portion or half of the shears. On a plane with the face of the

die-stand b is a yielding table, D, it having an opening through the center to allow the punch b to pass through it when pressed down by the action of the apparatus, the table D being supported on stiff springs d d underneath it and between it and the base A, and kept in its place by guiding-bars f f, secured to the under side of the table, passing down in guides c c at the ends of the base. The guiding-bars f f have a slit or long opening, g, at the lower end, into which a stop-block, i i, is put to hold the table D the right height.

On one edge of the table D is an arrangement for holding and placing the prints, so that they will lie on and in the center of the die-punch b to be cut. The prints are put in sheets into the spring-clamp E E, to correspond with the notches e e e, which are designed to stop and hold the sliding spring clamp by the aid of a spring catch, j, so that each print will be placed centrally on the card. There will be two or more of the spring-clamps with each machine, which are made by linging a cleat, F, onto the top of a beveled strip, E, with recesses in which to place a series of springs, n n, which act to keep the jaws closed, and are only forced open to put the prints in. They then have the mucilage spread on the sheet by the swab W, Fig. 9, which is made of a block of wood, the top part forming the handle x, the bottom part, y, being about the size of the card or print to be gummed, the face z z, and lower portion being covered with canton-flannel or its equivalent, this being dipped in the mucilage and passed once over the back of the sheet that contains the prints, four or more in number, after they have been placed in the clamp E. This process spreads the gum more evenly than can be done by a brush, and in less than one-fourth of the time, and the clamp is then slid into its place by the side of the yielding table D, the prints cut and pressed upon the cards by the mechanism hereinafter described.

I make a stiff iron frame, H H, which is placed vertically, so as to slide in metal boxes or guides h h h on each side of the base A in the center, the iron frame being one continuous piece all around. On the top is secured the angular shearing cutter frame I, the lateral sliding frame K K, to take the cards, one at a time, from the bottom of the receiver L, and place it centrally over the

opening or space which is surrounded by the cutters under the level face-block M, which brings it in contact with the gummed side of the print and compresses the two together.

There is an iron frame, N, into which the horizontal sliding frame K is fitted, so that it moves laterally to feed in and liberate the cards at each upward movement of the mounted mechanism by the action of the angular guide-bar C, which is secured to the base A, and passes between two friction-rollers, o o, or one roller working in a groove, the same being secured to the sliding frame K.

The card-receiver L is a box, made of wood or metal, and is mounted on and secured to the frame N or face-block R. The card-receiver being inside just the size and shape to fit the cards, and of sufficient depth to take in a pack of one hundred or more, they resting on their extreme ends on the sliding frame K, and are kept in close contact with it by the means of a peculiarly-constructed spring-follower, P, which is attached to the cover Q of the receiver L. The springs r r are so arranged and secured to the cover that the pressure is uniform upon the cards and exerts the same force on a single card or a whole pack. The follower P is secured to the cover Q by an upright pillar, S, which is placed in its center, passing through a hole in the cover. The pillar having a stop and knob, g, above the cover, by which it is known when the cards in the receiver are out without removing the cover, which is held firmly in its place by the double-acting buttons u u.

As the machine is being operated, which may be done by the foot on a lever connected with the sliding vertical frame H by means of a strap, rope, rod, or chain, to bring the cutting and pressing apparatus onto the die-punch, its motion upward being effected by a spiral spring, v, or its equivalent, placed in the base A between the under cross-bar of the frame H and the die-punch B. The same motion downward draws the horizontal sliding frame K in end and allows the bottom card to be pressed into the recess in the frame, so that with its motion back the card is carried into the place to receive the print and forced out by another card being placed in under the springs k k on the frame N. The shears or cutting blades c c are made angular on the lower or cutting edge, and are secured in the four sides of the frame I so that they fit on all sides of the die-punch b, thus forming perfect

shears. Another more simple and a cheaper mode of making the cutters is to have a right-angle flange on the upper edge, as seen in Figs. 3 and 3'. These cutters may be secured to the frame N by screws, and made adjustable, so that they can be set up and adjusted nicely to the die-punch b B, and taken off separately to sharpen and replaced. By making and securing the cutting-blades in this manner the frame or stock I is entirely dispensed with, the apparatus is lighter, is easier made, adjusted, and the cutters kept sharp, which is quite an essential feature in cutting the prints, so that their edges are smooth and nice.

The operation and effect produced by my invention has been generally shown, as the various parts have been described, but in addition I here remark that its advantages as a labor-saving machine for the purpose it is intended is immense, doing the work at least ten times faster than it can be done by the hand process, and in a much neater manner, there being no liability to deface the prints or the cards by handling and getting the gum on the prints. They are also placed centrally, or, as they are designed to be placed, all alike on an entire pack. The name of the artist or any device may be embossed or stamped on each card at the time the print is mounted by inserting a die or cut in the face-block or in the compressing die-punch.

Having thus fully described my machine or apparatus for gumming, cutting, and mounting photographic prints on cards, (*cartes de visite*), what I claim as new and useful, and desire to secure by Letters Patent, is—

1. The angular cutting-blades, so arranged and operated as to fit the die-stand or compressing-punch, the two forming shears to cut and mount photographic or other prints on cards in the manner herein described, for the purposes specified.

2. The sliding spring-clamp for the purpose of holding and gumming the prints and placing them centrally on the die-punch, in combination with the yielding-table, as herein described.

3. The combination of the card-receiver, the spring-follower, and the reciprocating frame, for alternately placing the cards in position to receive the prints and discharge the same in the manner herein set forth.

DANIEL H. CROSS.
